UNITED STATES PATENT OFFICE.

ALFRED ROWE BELLAMY, OF GRANTHAM, ENGLAND.

CHARCOAL-KILN.

1,168,845.

Specification of Letters Patent. Patented Jan. 18, 1916.

Application filed February 2, 1915. Serial No. 5,761.

To all whom it may concern:

Be it known that I, ALFRED ROWE BELLAMY, a subject of the King of Great Britain, residing at Spittlegate Iron Works, 5 Grantham, Lincolnshire, England, have invented new and useful Improvements in Charcoal-Kilns, of which the following is a specification.

My invention relates to kilns for charcoal 10 burning.

Charcoal kilns have already been proposed which comprise a body having a series of inspection and air holes distributed over it in a staggered formation, and provided with a charging opening at the top and a conical bottom fitted with a sliding door serving a double function, namely, that of controlling the discharge of the contents of the kiln, and of the inlet of air 15 into the bottom of the latter. In such kilns it is usual to depend upon the pieces of wood jamming in the conical bottom to prevent their falling through the kiln when the sliding door is open or partially open.

Now, according to my invention I make 20 use of a kiln which is composed of a body having a conical bottom as above described, the said bottom being furnished with a discharge opening which is designed to be 25 closed by a hinged drop-down door, which said door merely serves the purpose of controlling the discharge of the charcoal. Above the door the conical bottom is provided with a grate upon which the wood or 30 other material rests and having sliding bars, or any other suitable devices, so as to control 35 the flow therethrough of air which enters laterally the space between the said bars and the aforesaid door.

The body of the kiln is preferably made 40 in sections for easy handling and erection and is furnished with a series of air inlet holes which may advantageously serve as inspection holes as above described, and 45 these holes may be fitted with means, such as doors, whereby they may be opened or closed as desired. These holes may open directly into the interior of the kiln, or they may open into annular rings themselves in 50 communication with the interior of the kiln. Or, the introduction of air to the body of the kiln may be controlled in any other desired manner.

To enable my invention to be fully under-

stood, I will describe it by reference to the 55 accompanying drawings, in which:—

Figure 1 is a side elevation of a charcoal kiln made according to the invention. Fig. 2 is a sectional plan view thereof. Fig. 3 is a vertical section of the kiln. Fig. 4 is a 60 sectional view of the lower part thereof showing the discharge outlet opened. Fig. 5 is a view similar to Fig. 3 illustrating a modification, and Fig. 6 is a sectional plan 65 thereof. Figs. 7 and 8 are a front view and a vertical section, respectively, drawn to a larger scale illustrating one of the draught regulating doors, and Figs. 9 and 10 are two views similar to Figs. 7 and 8 of a modification hereinafter described. 70

a represents the body of the kiln, which is preferably made in sections as appears from Figs. 1, 3 and 5, the object of this construction being to facilitate the transport, erection and handling of the apparatus, the said sections being advantageously connected together in the manner herein- 75 after described.

b is the conical bottom of the body *a* and *c* is the discharge opening which is pro- 80 vided at the lower apex end of the said conical portion *b*.

d is the door for controlling the discharge of the charcoal, the said door being of the drop-down type and being hinged at *e* to a 85 frame *f* provided externally upon the bottom of the body *a* of the kiln below the discharge opening *c*.

g are the fire-bars which form a grate 90 upon which the wood or other material rests, the said bars being located above the door *d* and being arranged so that they can slide in holes *h* in the aforesaid frame *f* upon which the door *d* is hinged. The holes *h* constitute 95 inlets for air which thus enters laterally into the space *h*¹ between the discharge opening *c* and the door *d* when the latter is closed.

i are the inlet holes which are formed in the body *a* of the kiln and, in the construction illustrated, are arranged in a staggered 100 fashion over the surface thereof. These inspection holes are fitted with means, such as doors, whereby they may be opened or closed as desired. For example, in the construction illustrated in Figs. 1 to 8 doors *j* are 105 provided which are hinged at their upper parts *k* to frames *l* secured say by bolts to the outside of the kiln body *a* adjacent to the

said inlet openings *i*, holes *l* being provided in the said frames for receiving the bolts, the frames thus serve to connect together the sections of the body *a*. These doors *j* close the openings by gravity and are raised so as to more or less expose the openings *i* by means of thumb-screws *m* which engage screw-threaded holes in the upper parts of the said doors, and bear at their inner ends against the aforesaid frames *l*. Or, in lieu of hinged doors of the kind just described, I may make use of the arrangement illustrated in Figs. 9 and 10, such arrangement comprising a horizontally sliding door *n* which moves in guides in a frame *o* attached to the outside of the kiln body adjacent to the opening *i*, similarly to the frames *l*.

The air inlet, whatever be the nature of the door or the equivalent by means of which the passage of air therethrough may be regulated, may open directly into the interior of the kiln body, as shown in the construction illustrated in Figs. 1 to 4, or they may open into annular passages *p* as in the construction shown in Figs. 5 and 6. These annular passages *p* are formed in the body of the kiln and open at intervals, as shown at *q* into the interior of the kiln.

The kiln is utilized as follows, that is to say, the body has stacked within it the wood to be converted to charcoal, and the door *d* is opened and the fire-bars *g* placed in the position shown in Fig. 3. The wood is then ignited through the open bottom and when the combustion has started the door *d* is closed and all or any of the fire-bars can be drawn out or partially drawn out, as required, for properly regulating the admission of air through the holes *h* into the bot-

tom of the kiln body independently of the door *d*; also, as will be understood, the air inlets *i* to the body of the kiln are opened to an extent necessary to effect the proper control of the charcoaling operation.

Claims.

1. A charcoal kiln comprising a body, and a conical bottom provided with a discharge opening, a door controlling the said discharge opening, a grate located above the door and beneath the discharge opening and means for regulating the inlet of air independently of the door.

2. A charcoal kiln comprising a body, and a conical bottom provided with a discharge opening, a door controlling the said discharge opening, a grate located above the door and beneath the discharge opening and means for regulating the inlet of air through the grate independently of the door.

3. A charcoal kiln comprising a body, a conical bottom to the said body provided with a discharge opening, the said bottom having a grate located beneath said discharge opening, a discharge door located below the grate and means whereby the admission of air through the grate can be regulated independently of the door.

4. In charcoal kilns of the kind described, the combination with the kiln body, of a conical bottom therefor, a grate having a plurality of fire bars slidable in holes in a frame below the said grate, and a drop-down door hinged to said frame below said holes.

ALFRED ROWE BELLAMY.
